UNITED STATES PATENT OFFICE.

OSCAR ANTON WIBERG, OF FINSPONG, SWEDEN.

RADIAL FLOW TURBINE.

Application filed August 20, 1927, Serial No. 214,322, and in Great Britain August 30, 1926.

This invention relates to elastic fluid turbines, as steam or gas turbines, of the radial flow type having an axial flow system to be driven by the driving medium after it has 5 left the radial flow system.

The invention has for its object to provide an improved axial flow system for such turbines whereby the driving medium may be utilized in the best way possible by the axial 10 flow system. To this end the axial flow system includes a stationary guide blade wheel the passages of which are divided into a plurality of sections so dimensioned that a section of a smaller diameter has a narrow inlet 15 area and a wide outlet area as compared with the corresponding areas of a section of a greater diameter so that the velocities of the driving medium will be proportional to the peripheral velocities of the axial flow blading 20 at different radial distances from the turbine axis.

Other features will appear from the following description with reference to the accompanying drawing.

25 In the drawing, Fig. 1 is an axial section of part of a turbine according to the invention. Fig. 2 shows a detail on a larger scale. Fig. 3 is an axial section of a somewhat modified form of the guide blade disc of the axial 30 flow system.

The turbine illustrated is of the type having blade wheels running in opposite directions. It is to be noted, however, that the invention is not limited to said type of turbine.

35 With reference to the drawing the numeral 1 indicates the radial flow system of blade wheels.

Outside said radial flow blade system there 40 is provided an axial flow system represented in the drawing by a blade wheel 2 and a guide blade disc 3. The blade wheel 2 is carried by a ring shaped member 4 of the turbine disc.

45 The guide blade disc comprises an outer ring 5 and an inner ring 6 connected together by the guide blades proper 3. The guide blades 3 with the said rings 5 and 6 comprise a single piece made by casting. The 50 outer ring 5 is secured to the casing 7 of the turbine and forms part thereof, while the inner guide blade ring 6 extends towards the supporting ring 8 of the outermost blade drum of the radial flow system, said supporting 55 ring having, preferably, a packing edge 9 engaging the ring 6.

The guide blades 3 are provided with a dividing ring 10 to divide the driving medium coming from the blade wheel system 1 into two streams so as to cause positively part 60 of said driving medium to enter the axial flow system near the inner periphery thereof. Said dividing ring may either, as shown in Fig. 1, have a rather short radial extension or may, as shown in Fig. 3, extend inwardly 65 to the strengthening ring 13 of the outermost blade drum of the radial flow system. In such case, said strengthening ring 13 may be provided with a packing edge 14 to co-operate with the ring 10.

The areas of the guide blade disc 3 to be passed by the driving medium are chosen so that the velocities of the driving medium will be in proportion to the peripheral velocities at different radial distances from the axis of 70 the turbine. As a result, efficiency of the axial flow system will be as high as possible, the stresses being at the same time uniformly distributed, and the formation of undesired currents of the driving medium avoided.

75 In order to explain this result more clearly it should be noted that the same pressure exists at the two inlets to the channels of the drums at both sides of the partition 10 (see particularly Fig. 3). The pressure along the 80 outlet edge of the guide blade 3 is also practically the same along its whole length.

The drop in pressure being the same for the steam flowing on either side of the partition 10 is divided into a like number of 90 stages, each stage corresponding to a certain steam velocity. By allowing a larger pressure drop in the portion of the drums to the right of the partition the velocity of the steam to the right at its exit from the guide 95 blade 2 will be less than that of the steam to the left of the partition 10. In this way it is possible to obtain a relation of the steam velocity at the blade root to that at the blade top substantially equal of the relation of the 100 peripheral velocities at those points and, as a result, substantially uniform speed triangles will be obtained at all radii of the axial flow system so that the blades may be given a constant angle of inlet along its entire 105 length. This will, in turn, result in a higher efficiency and a more simple method of manufacture and so on.

In order to remove water from the steam, when steam is used as driving medium, before 110 it reaches the blades 2 there is provided at the outer edge of the ring 5 a water collecting

groove 11, Fig. 2, into which the water is led due to the action of the centrifugal force and whence the water may escape through apertures 12.

5. What I claim is:

1. In a radial flow elastic fluid turbine, the combination with an axial flow rotary blade system to be operated by the driving fluid after it has left the radial flow blade system, of 10 a non-rotary guide-blade system divided into a plurality of concentric sections so dimensioned that a section of a smaller diameter has a greater proportional increase in effective cross section than the section of a greater 15 diameter so that the velocities of the driving medium at different diameters of the axial flow blade wheel will be proportional to the peripheral velocities at said diameters.
2. In a radial flow elastic fluid turbine, the 20 combination with an axial flow rotary blade wheel to be operated by the driving fluid after it has left the radial flow blade system, of a non-rotary guide-blade disk divided into a plurality of sections so dimensioned that a 25 section of a smaller diameter has a greater proportional increase in effective cross section than the section of a greater diameter so that the velocities of the driving medium at different diameters of the axial flow blade 30 wheel will be proportional to the peripheral velocities at said diameters, and means on said guide blade disk to distribute uniformly the driving fluid along the entire length of blade of said disk.
3. In a radial flow elastic fluid turbine, the 35 combination with the radial flow blade system, of an axial flow rotary blade wheel to be driven by the fluid after it has left the radial flow system, a non-rotary guide-blade disk associated with said wheel, divided into a plurality of concentric sections, and a ring to divide the driving fluid into an inner and an outer stream on its way from the radial flow system to the axial flow system.
4. In a radial flow elastic fluid turbine, the 45

combination with the radial flow blade system, of a strengthening ring secured to the outermost blade drum of said system, an axial flow rotary blade wheel to be driven by the fluid after it has left the radial system, a 50 non-rotary guide-blade disk associated with said wheel divided into a plurality of concentric sections, and a ring secured to said disk and extending to said strengthening ring to divide the driving fluid into an inner and an outer stream on its way from the radial flow system to the axial flow system.

5. In a radial flow elastic fluid turbine the combination with the radial flow blade system, of a strengthening ring secured to the 55 outermost blade drum of said system, an axial flow rotary blade wheel to be driven by the fluid after it has left the radial system, a non-rotary guide-blade disk associated with said wheel divided into a plurality of concentric sections, a ring secured to said disk and extending to said strengthening ring to divide the driving fluid into an inner and an outer stream on its way from the radial flow system to the axial flow system, and packing 60 means between said strengthening ring and said driving ring.

6. In a radial flow elastic fluid turbine, the combination with an axial flow rotary blade system to be operated by the driving 75 fluid after it has left the radial flow blade system, of a non-rotary guide-blade system divided into a plurality of concentric sections so dimensioned that a section of a smaller diameter has a greater proportional increase in effective cross section than the section of a greater diameter so that the velocities of the driving medium at different diameters of the axial flow blade wheel will be proportional to the peripheral velocities at 80 said diameters, and draining means provided at the outer edge of said guide blade system.

In testimony whereof I have signed my name.

OSCAR ANTON WIBERG.
